UNITED STATES PATENT OFFICE.

ELMER E. NISWONGER AND DANIEL R. NISWONGER, OF DAYTON, OHIO.

ASSORTING-RECEPTACLE FOR LAUNDRIES.

No. 823,433.

Specification of Letters Patent.

Patented June 12, 1906.

Application filed April 20, 1904. Serial No. 204,013.

To all whom it may concern:

Be it known that we, ELMER E. NISWONGER and DANIEL R. NISWONGER, citizens of the United States, residing at Dayton, in the 5 county of Montgomery and State of Ohio, have invented certain new and useful Improvements in Assorting - Receptacles for Laundries; and we do hereby declare the following to be a full, clear, and exact description 10 of the invention, such as will enable others skilled in the art to which it appertains to make and use the same, reference being had to the accompanying drawings, and to the letters and figures of reference marked 15 thereon, which form a part of this specification.

Our invention relates to an assorting-receptacle for laundries, or, in other words, an assorting-bin for clothes, and although the device 20 can obviously be used for sorting and handling clothes under any conditions is especially and directly intended and designed for laundries doing a general public business.

Some of the main objects or purposes of 25 our invention consists in producing a device in the shape of a bin or receptacle adapted to properly hold rough-dried clothes in a manner so as to facilitate the time, labor, or work of assorting, it having been customary here- 30 tofore in the art to simply throw these clothes after having been dried from the wash in a promiscuous manner in any old basket, box, or other ordinary receptacle, thus causing a waste of time, labor, and floor-space, while 35 our device remedies all these numerous defects and yet keeps the clothes in better shape.

Among some of the principal advantages 40 of our invention resulting from the carrying out of the objects above referred to may be mentioned the following—to wit, convenience, saving in time, labor, and floor-space, simple in construction, inexpensive in cost 45 of manufacture, and one or more may be placed together in a row and each device can be multiplied to any desired height or width.

Our invention consists, essentially, referring 50 in general terms to the construction of the device, of a suitably-supported exterior portion or body having an open front, of a movable interior portion provided with several platforms upon which the clothes are placed, a front to each platform extending partially above it for retaining the clothes, the upper front being movable, means for 55 permitting of the raising or lowering of said interior portion or body, and the peculiar and

novel combination and arrangement of these various parts, as will be more fully described hereinafter in detail, and pointed out in the subjoined claim in accordance with the stat- 60 utes in such cases made and provided therefor.

Referring to the annexed drawings, constituting a formal part of this specification, and wherein the same letters and numerals have reference to like parts wherever occurring throughout the several views, Figure 1 is a view in front elevation of our assorting-receptacles for laundries, showing the interior portion in its normal position. Fig. 2 is a vertical longitudinal sectional view taken 65 on line xx of Fig. 3 in the direction indicated by the arrows. Fig. 3 is a transverse sectional view taken on line yy of Fig. 1 in direction indicated by arrows; and Fig. 4 is a detail plan view of a broken-away portion of the 70 top of the device, so as to show slot for front to project through.

In describing our said invention and referring in detail to the different parts or elements of construction of said receptacle or bin, as 75 illustrated throughout the various views of the annexed drawings and indicated by means of the letters and numerals of reference as aforesaid, A refers to the exterior portion or body preferably provided with casters 8 or 80 other supporting means, the top a and floor b being rectangular or square in form, thus making four sides to said exterior body, as shown by and can readily be understood from Fig. 3, the sides c and rear d being preferably 85 constructed of slats, the space between said slats allowing of a free and uninterrupted circulation of air through the clothes and also reducing the weight of the device, while the front e is open, (see more particularly Figs. 90 1 and 3,) through which the sorter or operator passes the rough-dried clothes to be 95 assorted onto the lower or upper or both platforms F and G, respectively, said platforms being connected by posts or uprights h , provided with upper and lower side and rear 100 braces k . For convenience lower platform F may be provided with cleats 9 for supporting same on the floor when lowered, if so desired.

Platforms F and G are provided with smooth-surfaced fronts f and g , respectively, front f being shown as rigidly connected to platform F, while front g is separate and independent of platform G and is provided 105 with lugs l , (see dotted lines Fig. 1 and solid lines Fig. 2,) which engage platform G

when raised. Said fronts extend upward only a short height, so as to permit of the clothes being passed over the top thereof onto the platform, and are provided with knobs or small handles *m* for raising the platforms, and thus bringing them to the height desired, and having a vertical movement in grooves *n*, located in the uprights or corner-posts of the front of the device, as clearly shown in Fig. 3, the lower front *f* being sufficiently narrower in width than the opening from said groove on one side to said groove on the other side, so that when said front is raised or lowered it will move or play laterally sufficiently loose in grooves *n*, so as to pass a small stop *o* (located in one of said grooves) and which supports front *g* when said front is down and the parts are in normal position, as shown in Fig. 1. The platforms, the fronts, and the posts *h* connecting said platforms constitute what may be for convenience of description here termed the "interior" portion or body of the device.

Fronts *f* and *g* are provided with a black-board, upon which the sorter can mark or indicate with a piece of white chalk or crayon the initial letters, numbers, or name or other mark upon the clothes and the number of articles or any other memorandum desired relating to the clothes being assorted, as shown and indicated for convenience upon the drawings by means of surface shading, as at 10, Fig. 1. Front *g* is provided with a small plate having a lip *p*, adapted to engage a spring-catch *q* for supporting said interior body through the medium of lugs *l* engaging platform *G* when raised by means of its knob or handle *m*, as shown in solid lines in Fig. 2 and broken away in dotted lines in Fig. 1.

Cables or ropes *r* are connected at one of their ends to platform *G*, (see Figs. 1 and 2,) each passing over pulleys or small wheels *s* and *t*, suitably attached to the device, as shown, and to their opposite ends are attached a weight *u*, which holds the interior portion or body when raised to the different heights or positions for the convenience of

operator when sorting, as shown in solid and dotted lines in Fig. 2, there being the usual amount of frictional contact to assist in supporting when said interior body is moved.

As clearly shown in plan in Fig. 4 of a portion of the top *a*, a slot 12 is formed through the top near the front edge sufficiently long so that front *g* can extend or project upward therethrough when the interior body is raised as high as top *a* will permit, as shown in dotted lines in Fig. 2.

We wish to be here understood as still reserving to ourselves the right under the well-known and long-established doctrine of patent law of making any minor changes in the arrangement or construction of the various parts of our device as may from time to time be suggested or found necessary, so long as within the scope and spirit of the invention and without departing from the principles of the same.

We are of course well aware of other devices of a somewhat similar nature—such as dumb-waiters, for example—in which a body or portion has a vertical movement by means of a cable and weight attached thereto. Therefore we do not, of course, claim these features, broadly; but

As we know our particular combination of elements are new and patentable, therefore what we claim is—

The combination in an assorting-receptacle for clothes; of the exterior slatted body having a floor and a top provided with a longitudinal slot; the interior body formed by the movable platforms connected by posts or uprights; said platforms having the smooth-surfaced fronts, one of which is provided with lugs for engagement with its platform; and the pulleys, cables and weights for operating said body.

In testimony whereof we have affixed our signatures in presence of two witnesses.

ELMER E. NISWONGER.
DANIEL R. NISWONGER.
